UNITED STATES PATENT OFFICE

PIERRE L. DORNER, OF EVANSTON, ILLINOIS

FILTER PRESS

Original application filed August 10, 1927, Serial No. 211,981. Divided and this application filed May 11, 1929. Serial No. 362,409.

My invention relates more particularly to filter presses forming elements of so-called dry cleaning apparatus for cleaning fabrics and employing a liquid cleaning material, as for example benzine, which it is desired be cleaned of objectionable matter, such as dirt, discoloring matter and water which becomes mixed with it in the dry cleaning operation, and when it becomes acid in condition; the present application being a division of my pending application for United States Letters Patent Serial No. 211,981, filed August 10, 1927.

One of my objects is to provide a filter press the several filtering sections of which wherein the liquid to be cleansed is treated in succession, may be separately charged with the desired filtering material; and other objects as will be manifest from the following description.

Referring to the accompanying drawings:

Figure 1 is a plan view of so-called dry-cleaning apparatus embodying my improvements.

Figure 2 is a sectional view in elevation of the apparatus of Fig. 1, the section being taken at the line 2-2 on Fig. 1 and viewed in the direction of the arrow.

Figure 3 is a view in elevation of the washer, mixer and connections therebetween forming portions of the apparatus of Fig. 1, the mixer being shown in section, this view being taken at the irregular line 3-3 on Fig. 1 and viewed in the direction of the arrows.

Figures 4 to 10, inclusive, are detailed views of certain portions of my improved filter-press forming a part of the apparatus of Fig. 1; Fig. 4 being an end view of the filter-press as viewed from the right-hand side of Fig. 2; Fig. 5, a face view of one of the plurality of heads forming a portion of the filter-press; Fig. 6, a face view of the head at the other end of the press; Fig. 7, a face view of one of the plurality of ribbed plates constituting parts of the filter-press; Fig. 8, a face view of one of the hollow frames forming parts of the filter-press; Fig. 9, an enlarged view in vertical, longitudinal, sectional elevation of a portion of the filter-press, the section being taken at the line 9 on Fig. 7 and

viewed in the direction of the arrows; and Fig. 10, an enlarged plan sectional view through a portion of the filter-press, the section being taken at the line 10 on Fig. 8 and viewed in the direction of the arrow; and Fig. 11, an enlarged, broken sectional view taken at the irregular line 11-11 on Fig. 5 and viewed in the direction of the arrows.

Referring to the particular illustrated embodiment of my invention, the dry-cleaning apparatus shown comprises, generally stated, a washer represented generally at 11 in which the fabrics to be cleaned are subjected to the cleaning liquid; a mixer represented generally at 12 in communication with the outlet 65 of the washer 11 through which the cleaning liquid passes and in which, preliminarily, the substances to be charged into the filter-press are mixed with the liquid; a filter-press represented generally at 13 for cleaning the 70 liquid withdrawn from the washer and returning it to the latter in cleansed condition for reuse; and a pump represented generally at 14 for effecting the desired circulation of the liquid through the apparatus. 75

Referring now to the washer 11, which may be of any desirable construction, such as the general construction now commonly in use, it comprises a tank portion 15 containing a holder (not shown) for the articles 80 to be cleaned, such as clothes to be dry-cleaned, this holder being mounted on a shaft 16 journaled in the ends of the tank 15 and rotated, preferably intermittently in opposite directions, by power applied to a drive 85 pulley 17 in any suitable way and transmitted to the shaft 16 as through the gearing represented generally at 18. The tank 15 is in communication at its upper end with the depending branches 19 of a pipe 20 connected 90 with a pipe 21 which leads from the outlet of the filter-press 13 and through which the cleansed cleaning liquid is supplied to the tank 15.

The mixer 12 comprises a receptacle 22 95 containing a power-driven mixer, or agitator, device 23 mounted on a vertical shaft 24 and adapted to be driven from a drive shaft 25 through the medium of bevel gears 26, the tank 22 preferably containing an air vent 100

represented at 27 and communicating at its lower portion with a pipe 28 depending into the tank through its top.

The washer 15 and mixer 12 are preferably located in substantially the same horizontal plane, as shown, and are in communication with each other through a pipe 29 which opens at one end into the bottom of the tank 15 and at its other end into the bottom of the tank 22 this pipe being equipped with a manually-controlled shut-off valve 30.

The pump 14 may be of any desirable construction and may be driven in any suitable way, its suction inlet being in communication with the pipe 28 and its outlet opening into a pipe 31 which leads to the filter-press 13.

Opening into the pipe 31 between the filter-press 13 and the pump 14 is a pipe 32 which is provided between its ends with a manually-controlled shut-off valve 33 and extends at its depending portion 34 downwardly into the lower portion of the tank 22 through the top of the latter. The pipe 32 between the pipe 31 and the mixer 12 communicates with a pipe 35 which is provided with a manually-controlled shut-off valve 36 and opens into the upper portion of the tank 15.

The filter-press 13 is formed of a plurality of filter sections the press shown comprising three of such sections represented generally at 37, 38 and 39, though the number thereof may be varied as desired, these sections being separated by heads 40 and 41.

Each of the filter-press sections 37, 38 and 39 are shown as of the same general construction and comprise elements of a form and grouping as is common in filter-press constructions, these elements comprising rectangular frames 42 alternating with rectangular plate-members 43, with sheets 44 of fabric interposed therebetween. Each of the frames 42 contains at one corner thereof a through-passage 45 extending crosswise thereof and at its diagonally-disposed corner a through-passage 46 extending transversely thereof and opening into the center of the frame through a port 47. Each of the plate-members 43 contains at opposite faces thereof grooves 48 wholly within the confines of the margin of the plate-member which latter is slotted at the bases of said ribs as represented at 49, these slots communicating interiorly of the plate, through ports 50, with through-passages 51 at the corner-portion of each plate, the diagonally opposite corner of each plate containing a through-passage 52.

The elements forming the filtering sections 37, 38 and 39, together with the heads 40 and 41 are rigidly clamped between end heads 53 and 54 which are supported on a pair of parallel rods 55 and 56, the head 54 abutting nuts 57 at ends of these rods and the head 53 being forced toward the head 54 with the filter sections 37, 38 and 39 and heads 40 and

41 interposed therebetween as shown, by a shaft 57 threaded in a cross-member 58 which abuts nuts 59 on the adjacent ends of the rods 55 and 56.

The sections 42 and 43 are grouped to alternate with each other as above stated and in the relative positions illustrated, these elements resting on the rods 55 and 56 at lugs 60 and 61 thereon, to cause the openings 45 and 51 of these elements to register with each other and also cause registration of the openings 46 and 52, thereby forming at diagonally-opposed corners of these grouped elements, at each filter section, continuous passages extending from one end to the other of each filter section, the passages formed by the openings 46 and 52 being inlet passages and the passages formed by the openings 45 and 51 being outlet passages.

The intermediate heads 40 and 41 which are alike in construction are formed with lugs 40^a and 41^a, respectively, at which they rest on the rods 55 and 56, each of these heads being formed at opposite faces thereof with recesses 62 and 63, the recess 62 communicating with a passage 64 which opens into a passage 65 in the head, the passage 65 having a portion which registers with the passage formed by the openings 45 and 51 in the frames and plates 42 and 43, respectively, and extends upwardly through the top of the head, and the recess 63 communicating with a passage 66 which opens into a passage 67 in the adjacent face of the head in alignment with the passage formed by the openings 45 and 51 in the frames 42 and plates 43, respectively, and extends upwardly through the top of the head and at its opposite end through a face of the head and in registration with the openings 46 and 52 in the frames 42 and the plates 43, respectively.

The passages 65 and 68 of the head 40 are connected together by a pipe 69 containing a sight-glass 70 and a three-way valve 71, and the passages 65 and 68 of the head 41 are connected together by a pipe 72 containing a sight-glass 73 and a three-way valve 74.

The pipe 31 is branched to afford the branches 75 and 76 provided with manually controlled stop-valves 77 and 78, respectively, and opening, respectively, into the three-way valves 71 and 74, the pipe 31 between the pump 14 and the branch 75 communicating at a three-way valve 79 with a pipe 80 which connects with a through-passage 81 in the head 53 registering with the passage formed by the openings 46 and 52 in the frames 42 and plates 43, respectively, of the filter-press section 37.

The end head 54 contains in its inner face a recess 82 communicating, by a port 83, with a through-opening 84 in this head at one corner thereof and in registration with the

passage formed by the openings 45 and 51 of the frames 42 and plates 43 constituting the filter-press section 39, this passage 84 communicating with the pipe 21.

5 It will be understood from the foregoing that the passage formed by the registering openings 46 and 52 of the frames 42 and plates 43 of the filter-press section 37 are in communication with the pipe 80 and that 10 the outlet passage formed of the openings 45 and 51 in these frames and plates are in communication with the passage 65 of the head 40; that the passage formed of the openings 46 and 52 of the frames and plates 15 of the filter-press section 38 are in communication with the passage 68 of the head 40 and the passage formed by the openings 45 and 51 of the frames and plates of this filter-press section are in communication with the passage 65 of the head 41; that the passage formed by the openings 46 and 52 of the filter-press section 39 are in communication with the passage 68 of the head 41; and the passage formed by the openings 45 and 51 of 20 the frames and plates of this section are in communication with the passage 84 of the head 54 and consequently the pipe 21.

It may be further stated that the three-way valves 71, 74 and 79, are of common 30 construction, the valve 71 being adapted to close the passage 68 of the head 40 to the passage 65, through the pipe 69, or to open it to the passage 65 and close it to the pipe 75, or close the passage 68 to the passage 65 35 and open it to the pipe 75; that the valve 74 is operable either to close the passage 68 of the head 41, or open it, to the passage 65 of this head through the pipe 72, or close the passage 68 to the passage 65 and open it 40 to the pipe 76; and that the valve 79 is operable to shut off the flow through the pipe 31 at this point or open it either to the pipe 80 or to the pipes 75 and 76.

It may be further stated that liquid to be 45 filtered entering the inlet passage of any one of the three filter-press sections and formed by the openings 46 and 52 thereof, flows throughout the length of the section and branches off from this inlet into the interiors of each of the frames 42 thereof, thence passing laterally through the filtering cloths 44 and into the recessed portions 50 of the plates adjacent thereto from which it discharges through the openings 50 into 55 the outlet passage formed of the openings 45 and 51.

In the particular construction of filter-press illustrated and described the cleaning liquid withdrawn from the washer 11 is 60 subjected to a filtering action for restoring the liquid substantially to its original condition and to this end removes its contained dirt, the substances therein which cause the liquid to be discolored, and water, and where 65 the liquid contains acids removing the lat-

ter therefrom. This filtering operation is effected by charging into the section 37 of the filter-press through the inlet thereof any desirable powdered cellular material, as for example kieselguhr mixed preferably with the cleaning liquid as for example benzine; by charging into the section 38, through its inlet, any suitable decolorizing substance, as for example a mixture of powdered charcoal, cellular material, such as kieselguhr, and preferably the cleansing liquid, the charcoal operating to absorb the material in the cleansing fluid which gives to it its undesirable color. The section 39 may be used without any filter substance charged 70 into it, but where it is desired to remove acid from the cleansing liquid this section should be charged, in the manner described of the other filter-press sections, with a basic compound, such as lime salts.

In the arrangement shown the filter-press sections may be separately charged with the desired materials, as for example those above described, from the mixer 12 in which the several different materials are separately 80 mixed with the liquid and the valves between the pump 14 and the several filter sections manipulated to conduct the several filtering substances referred to into the respective filter sections, this being possible 85 as the valve connections described permit of the pumping of the mixture of liquid and filtering substance from the mixer 12 to any one of the filter-press sections to 90 the exclusion of the others thereof.

As is well known in the art, the flowing 95 of the mixture of liquid and filtering substance into the inlet passage of a filter section, the mixture flowing into the interiors 100 of the frames 42 and between layers of the filtering cloth 44, causes the filtering substance to be intercepted by these filtering cloths and results in the formation of cakes 105 of the filtering substances within these frames through which the liquid to be cleansed is caused to flow in the filtering operation.

It may be further stated that by the arrangement of piping and valves as shown the washer 11 may be operated without circulation of the cleaning liquid until the liquid therein becomes too dirty for use, whereupon the valves 30, 79, 33 and 36 may be adjusted to provide a continuous course from the washer 15 through the mixer 12 and pump 14 110 back to the washer thereby causing the clean 115 cleaning liquid in the mixer 12 to become intermingled with the dirty cleaning liquid and in such condition to be used for cleaning until the mixture of such liquids becomes too 120 dirty for use, whereupon the various valves are manipulated to cause the cleansing liquid to flow from the washer 11 through the mixer 12, pump 14, and filter-press sections 125 37, 38 and 39 in succession and then back into 130

the washer 11, the cleaning liquid in flowing through these filter-press sections being restored substantially to its original condition.

In apparatus of this general character it is desirable that means be provided for regulating the pressure at which the mixture of liquid and filtering substance is supplied to the several filter-press sections, to ensure against the formation of cakes of the filtering substance in the filter-press sections of too great a density. This is provided for by the valve 33 which, in the process of forming the filter cakes, is partially open which results in the diversion from the pipe 31 and into the mixer 12, of a portion of the discharge from the pump 14, thereby reducing the pressure supplied to the filter-press sections. As the cakes form in the filter-press sections, thereby creating certain resistance to the passage of liquid through the filter-press, the operator, by manipulating the valve 33, decreases the liquid flow back to the mixer and increases the flow and pressure to the filter-press with the result that cakes of the desired porosity are formed in the filter-press and the desired volumetric flow of liquid therethrough, to render the apparatus continuous in operation, is effected.

The location of the washer 11 and mixer 12 in substantially the same horizontal plane, together with the communication therebetween at their lower portions as provided by the pipe 29 the latter being of such diameter that the level of the liquid in the washer will be substantially the same as the level of the liquid in the mixer at all times under the operation of the pump, is of particular advantage as thereby danger of over-flowing the washer is avoided.

While I have illustrated and described a particular construction embodying my invention I do not wish to be understood as intending to limit it thereto as the same may be variously modified and altered without departing from the spirit of my invention.

What I claim as new, and desire to secure by Letters Patent, is:

1. A filter-press formed of filter sections, a conduit for conducting into one end of one of said sections liquid to be cleaned, a conduit for conducting from said section into the next section all of the liquid introduced into said first-named section, a conduit leading away from said last-referred-to section, a conduit communicating with said second-named conduit, and controlling means whereby communication between said sections through said second-named conduit and communication between said fourth-named conduit and said second-named conduit may be controlled.

2. A filter-press formed of filtering sections separated by a head having a passage connecting the outlet of one of said sections with the inlet of the other of said sections, a

conduit communicating with said passage for the conducting into said last-referred-to section of all of the liquid introduced into the first-referred-to section, and controlling means whereby communication between said sections through said passage and between said conduit and said passage may be controlled whereby liquid may be caused to flow through one only of said sections or all of the liquid caused to flow, in succession, through both thereof.

3. A filter-press formed of filtering sections separated by a head containing a passage connecting the outlet of one of said sections with the inlet of the other of said sections, a pipe for leading liquid to be filtered into the inlet of said first-referred-to sections, a pipe communicating with said passage for leading liquid to be filtered to said passage, and valve means adjustable to permit flow from said outlet through said passage and thence to said inlet of all of the liquid introduced into said first-referred-to section, or arrest the flow from one section to the other and open said passage to said second-named pipe for the supplying of liquid to said second-referred-to section to the exclusion of said first-referred-to section.
